(57) **CLAIM**

I claim the ornamental design for the light housing, as shown and described.

DESCRIPTION

FIG. 1 is a front perspective view of a light housing embodying my new design;

FIG. 2 is a top plan view thereof, the bottom view a mirror image of the top view;

FIG. 3 is a front elevational view thereof;

FIG. 4 is a side view thereof, the opposite side view being a mirror image thereof; and,

FIG. 5 is a rear view thereof.
